UNITED STATES PATENT OFFICE.

JOHN W. FAESSLER, OF MOBERLY, MISSOURI.

POLISHING-WHEEL.

SPECIFICATION forming part of Letters Patent No. 769,309, dated September 6, 1904.

Application filed March 3, 1904. Serial No. 196,442. (No model.)

To all whom it may concern:

Be it known that I, JOHN W. FAESSLER, a citizen of the United States, residing at Moberly, Randolph county, Missouri, have invented certain new and useful Improvements in Polishing-Wheels, of which the following is a specification, containing a full, clear, and exact description, reference being had to the accompanying drawings, forming a part hereof.

10 My invention relates to an improved polishing-wheel, and has particular relation to that class of polishing-wheels in which the polishing is effected by means of strips of emery-paper and the like removably mounted upon the periphery of a driven wheel.

15 In the drawings, Figure 1 is a perspective view of a wheel embodying my invention. Fig. 2 is an enlarged view of a portion of such wheel embracing a side view of the clamping device employed. Fig. 3 is a perspective view of the portion of the wheel shown in Fig. 2. Fig. 4 is a transverse sectional view of the same taken along the line 4-4 in Fig. 2. Fig. 5 is a perspective view of the clamping-arm.

20 In the drawings, the strip of polishing material is indicated by the numeral 1, and it is mounted upon the face of the flat face band-wheel 2. In practice in the art to which my invention relates such band-wheels are usually made of metal, and in order to provide a measurably resilient polishing-surface which will protect the article being polished from injury during the operation of polishing I have provided the strip 4, which is of felt or like material and which is glued or otherwise affixed upon the outer face of the rim 3 to serve as a cushion for the polishing-strip 1.

25 It is indispensable to the successful operation of a polishing-wheel that the polishing-surface should be substantially continuous, seamless, and unbroken. To that end I have provided the rim 3 with the outwardly-projecting flanges 5 and 6, which are of a height equal to the thickness of the strip 4 and over which the strip 1 is to be tightly drawn, as indicated in the drawings. When the strip 1 is placed in position upon the wheel, its ends pass inwardly between the flanges 5 and 6 through the slot 7 and into the opening 8. The 30 ends of the strip 1 are then tightened by being

drawn into a roll, which roll is indicated by the numeral 9 in Fig. 1. The winding of this roll is best accomplished by means of the ordinary split key, which is well known in the art, and is therefore not shown in the drawings. 55 The strip 1 is then locked in position by straightening the clamping-arm 10, which is a flexible double arm pivotally mounted in the wheel 2 by means of the pin 11, the arm 10 being broken about midway its length and the 60 parts pivotally connected together by means of the pin 12. The end of the arm 10 is provided with the jaw 13, which is adapted to thrust the end of the strip 1 into the corresponding recess 14 in the member 15, with 65 which the flange 6 is shown in the drawings as being integral. In order to permit the introduction of the ends of the strip 1 to the opening 8, the arm 10 is forced to an unlocked position, as shown in Fig. 3, the pin 10 being 70 thrown toward the center of the wheel 2 in the slot 16. When the strip 1 has been tightened, the arm 10 is straightened to the position shown in Fig. 2, when the pressure of the jaw 13 against the recess 14 will hold the strip 1 75 securely in place. This manipulation of the arm 10 will be reversed when it is desired to remove the strip 1 from the wheel.

I claim—

1. In a polishing-wheel: the wheel 2 having an opening 8 and a slot 16; the rim 3 upon the wheel and having the transverse slot 7 communicating with the opening 8; the flanges 5 and 6 extending outwardly from the rim, one upon each side of the slot 7; the cushion 4 80 upon the outer face of the rim and butting against the flanges 5 and 6; the clamping member 15 upon one side of the slot 16 in a radial line with the flange 6, and having the angular recess 14 in its clamping-face; the strip 1 of 85 polishing material upon the cushion with its ends extending over the flanges 5 and 6 and through the slot 7 into the opening 8; the clamping-arm 10 having a clamping-face in 90 opposition to the recess 14; said clamping-arm 95 being connected to the wheel by a toggle-joint, so as to grip the polishing material in the recess 14; substantially as specified.

2. In a polishing-wheel: the wheel 2 having an opening 8 and a slot 16; the rim 3 hav- 100

ing the transverse slot 7 communicating with the opening 8; the clamping member 15 having the angular recess 14 in its clamping-face; the strip of polishing material upon the rim 5 with its ends extending through the slot 7 into the opening 8; the clamping-arm 10 having a clamping-face in opposition to the recess 14; said clamping-arm being connected to the wheel by a toggle-joint, so as to grip the pol-

ishing material in the recess 14; substantially as specified.

In testimony whereof I have signed my name to this specification in presence of two subscribing witnesses.

JOHN W. FAESSLER.
